United States Patent Office

Des. 205,265
Patented July 12, 1966

205,265

COMBINED TABLE AND MASSAGING UNIT THEREFOR

Frank C. Catanzaro, 6212 McPherson Ave.,
University City, Mo.

Filed July 2, 1965, Ser. No. 86,020

Term of patent 14 years

(Cl. D83—1)

FIG. 3 is a rear elevation rotated 180 degrees from FIGS. 1 and 2;

FIG. 4 is an end elevation taken from the left of FIG. 3; and

FIG. 5 is an end elevation taken from the right of FIG. 3.

I claim:

The ornamental design for a combined table and massaging unit therefor, substantially as shown.
